A. B. COLBY

PIN FASTENING DEVICE

Filed June 30, 1927

UNITED STATES PATENT OFFICE.

ALLAN B. COLBY, OF PROVIDENCE, RHODE ISLAND.

PIN-FASTENING DEVICE.

Application filed June 30, 1927. Serial No. 202,568.

The present invention relates to a pin having a head plate and has as one of its objects the provision of a durable and cheap structure of the type mentioned.

5 A second object of the invention is to provide a head structure well adapted for a double pronged pin and capable of rapid manufacture.

10 Another object of the invention is to provide a rapid and cheap method of manufacturing pins having rigid head plates.

15 With these and other objects in view the invention consists of certain novel features of construction and of operation as will be 15 more fully described and particularly pointed out in the appended claims.

In the accompanying drawing:

Figure 1 is an elevation of a complete pin according to the present invention.

20 Figure 2 is a view taken from the right of Figure 1.

Figure 3 is an elevation of an ordinary bank pin used in making the article shown in Figures 1 and 2.

25 Figure 4 is a central vertical section through the pin illustrated in Figure 1.

Figure 5 is a view taken on the right of Figure 2, the cap piece having been removed.

30 Figure 6 is a section taken on the line 6—6 of Figure 5 looking in the direction of the arrows.

Figure 7 is a central section through the cap piece appearing in Figures 1, 2 and 4, illustrating said piece prior to its attachment 35 to the head plate to which the pin or pins is or are affixed.

Figure 8 is an elevation of one form of head plate according to the present invention and appearing in Figures 4, 5 and 6.

40 Figure 9 is an elevation of a modified form of head plate having pins attached thereto.

Figure 10 is a section taken on the line 10—10 of Figure 9 looking in the direction of the arrows.

45 Figure 11 is a view of another form of head plate having pins attached thereto.

Figure 12 is a section on the line 12—12 of Figure 11 looking in the direction of the arrows and showing a central flange portion

50 in the head plate extending into the greatest depth of the cap member.

Figure 13 is an elevation of a double pin according to the present invention including a modified form of cap and the head plate of the type illustrated in Figures 9

and 10, the cap being designed to act as part of a snap fastener.

Figure 14 is a section on the line 14—14 of Figure 13.

Figure 15 is an elevation of the double 60 headed pin employing still a different form of cap, a socket member of the ordinary type of snap fastener being held within the cap.

Figure 16 is a central horizontal section through the device illustrated in Figure 15. 65

It has been known to make a pronged pin of a single piece of wire bent into a shape permitting the attachment of a cap or head thereto. Such pins, however, have required expensive machinery for their manufacture. The ordinary headed straight pins, such as bank pins, however, are manufactured in enormous quantities and can be 70 bought very cheaply in large lots.

In the drawing, I have illustrated a pin 75 according to the present invention and having a relatively large head, and which is made from one or more pins of ordinary type and a special head structure.

Referring to the drawing, 20 indicates a 80 head plate to which one or more pins is to be secured. The plate 20 may be made rigid if desired sufficiently to stand the stress it is expected to encounter in use.

Preferably the pins connected to the plate 20 are of the ordinary type having a pointed shank 22 and a small round head 24. In the device illustrated in Figures 1, 2 and 4 two pins 22 are attached to the plate 20. In

the embodiment illustrated in Figures 1, 2, 4, 5 and 6, plate 20 is notched to provide two pairs of aligned slots 26, 26 and 28, 28, respectively. A pin is secured to plate 20 by inserting its head 24 into a slot 26, then bending the pin in a plane perpendicular 90 to the plane of the plate so that the portion 30 of the shank lies parallel to and in contact with one face of plate 20 and overlies the other slot 26. The pin 22 is then bent

again so that a curve or bent portion 32 95 lies in the other slot 26, the part 30 being short enough to prevent head 24 or bend 32 from slipping out of the end of its slot 26.

Preferably, also, the pin is bent sufficiently 100 so that the remainder of the shank 22 of the pin also lies approximately parallel to the plate 20. The operation just described is then repeated, if desired, with respect to another pin and the slots 28, 28 so as to attach the second pin 22 to the plate 20 or 110

both pins may be thus positioned simultaneously, if desired. After one or more pins has or have been secured to the plate 20, it is preferred to secure a cap 34 to the plate. The cap may be secured to the plate 20 in any convenient manner but preferably this is done by rolling or crimping the margin of one member over that of the other. In the arrangement illustrated in Figures 1 and 2 cap 34 is first struck up from a blank into the form of a round cup having a cylindrical flange, the plate 20 is then inserted therein and secured thereto by rolling inwardly the edge of the flange so that the cap 34 embraces the edge of the plate 20, as illustrated in Figure 4. It will be seen that the cap 34 lies close to the portion 30 and pins 22 so that the pins 22 are prevented from substantial movement perpendicular to plate 20 and are held in their interlocking engagement with plate 20 irrespective of the heads 24 of the pins. It will be seen, therefore, that while the use of headed pins is convenient, the present invention is not limited to headed pins. Moreover, if the portion 30 of the pins is long enough to let the pins slip out of slots 26 or 28, the cap 34, or the like, acts to prevent the pins leaving the ends of the slots either at the head 24 or at the bend 32. In Figures 9 and 10 is illustrated in modified form a head-plate 20^a. Plate 20^a has an apertured segment 38. Segment 38 is bent substantially at right angles to the body of the plate 20^a and is apertured as illustrated at 40. Two or more of the apertures 40 may be made in the flange or segment 38, one of which appears in Figure 10. The apertures 40 are each in alignment with one of the slots 26, 28 in the opposite edge of the plate 20^a.

In securing pins to plate 20^a a pin is run through one of the apertures 40 with its head towards the outside of the segment 38 of the plate, the shank 22 of the pin extending along the plate 20^a and the pin is then bent around the plate to bring the curved neck or bend 32 within the slot 26 or the like in the opposite edge of the plate 20^a and preferably so the shank 22 lies approximately parallel to plate 20^a. It will be evident that the pins have interlocking engagement with the plate 20^a.

In Figures 11 and 12, I have illustrated still another form of head-plate 20^b. Plate 20^b is formed by making a cut in the plate to define a segment 38^a and then bending the segment 38^a at right angles to the body of the plate. By cutting plate 20^b parallel to its outer circumference as just described, segment 38^a can be positioned as illustrated in Figure 12 so that it extends outwardly into the cap at the centre of the cap and where there is the most room between the cap and the plate to receive the segment.

Segment 38^a has apertures 40^a therein in alignment with the slots 26 and 28 in the outer edge of plate 20^b. A pin may be secured to the plate 20^b by the same method as previously described in connection with the attachment of pins to plate 20^a.

It has been known to provide double pronged pins with means such as snap fasteners of the type used on gloves for releasably attaching articles to the pins. In Figures 13 and 14 is illustrated a double pin according to the present invention provided with a cap arranged to act as a socket member of a glove type fastener. In Figures 14 and 15, I have illustrated a cap 34^b, the center of which is punched inwardly to provide a segmental opening 42. The edges of this opening 42 are bent inwardly, as illustrated at 44 and are also cut along radial lines, as illustrated at 46. By the arrangement just described the cap 34^b is adapted to releasably retain the boss or head of a glove type fastener stud, the edges of opening 42 being adapted to spring to one side to admit the head of the stud and to contract again after it has been forced through the opening 42. Cap 34^b is illustrated in connection with the head plate 20^a but may be used with any kind of head plate desired. Cap 34^b has a flattened front face to facilitate its use as a part of a snap fastener and as illustrated is provided with a distinct groove 48 just within its outer edge forming a socket for the edge of the plate 20^a. However, the use of the groove 48 is a matter of choice.

In Figures 15 and 16, I have illustrated a pin having a cap piece or member 34^c. The pin illustrated in Figures 15 and 16 is also designed for use as a part of a snap fastener, the cap member 34^c having a central opening 42^a to permit the insertion of the stud member of the snap fastener.

Cap 34^c, however, is deep enough to provide room between the plate 20 and the inner face of the cap for a socket member 50 of the type ordinarily used in snap fasteners. The cap 34^c is similar to cap 34^b in that it has a distinct shoulder and a flange on its edge forming a groove 48 for receiving the edge of the head plate 20, or the like.

I have herein shown and described the end of the pin stems as being upset to form a head but the head may be formed in any desired way to perform the function of the upset portion.

The foregoing description is directed solely towards the constructions illustrated but I desire it to be understood that I reserve the privilege of resorting to all the mechanical changes to which the device is susceptible, the invention being defined and limited only by the terms of the appended claims.

I claim:

1. The combination of a head plate hav-

ing alinged openings in its edge, a pin having a portion extending across the face of said plate and having a portion bent to lie in one of said openings, and a cap member 5 fixed to said plate in position to prevent material movement of said pins in a direction perpendicular to said plate.

2. The combination of a head plate having aligned openings in its edge, a headed pin bent around said plate, said pins having a head held in one of said openings and having a bent portion lying in the other of said openings, and a cap member having 10 its margin embracing the margin of said 15 plate.

3. The method of fastening a headed pin to a plate comprising slotting the edge of the plate engaging the head of the pin with one of said slots in the plate and bending the

pin around the plate and into another slot 20 in the opposite edge of the plate.

4. The method of fastening a headed pin to a plate comprising forming aligned slots in the margin of the plate, engaging the head of the pin in one of said slots and 25 bending the pin around the plate and into the other of said slots, and applying a cap to the margin of said plate to cover said slots at the marginal edge of the plate.

5. The combination of a head plate having a slotted edge, a pin member having a head portion secured to said plate and having a bend lying in the slot in said edge, and a cap fixed to said plate to extend 30 across said slot opening to lock the bent portion of said pin member in said slot. 35

In testimony whereof I affix my signature.

ALLAN B. COLBY.
